SPARK-PLUG.

1,276,396.

Specification of Letters Patent. Patented Aug. 20, 1918.

Application filed October 21, 1916. Serial No. 126,954.

To all whom it may concern:

Be it known that I, ARDEN J. MUMMERT, a citizen of the United States, residing at St. Louis, State of Missouri, have invented 5 certain new and useful Improvements in Spark-Plugs, of which the following is a full, clear, and exact description, reference being had to the accompanying drawings, forming a part hereof.

10 My invention has relation to improvements in spark-plugs; and it consists in the novel features of construction more fully set forth in the specification and pointed out in the claim.

15 The present improvement is directed to the construction of spark-plugs for explosive engines, and has for its object the construction of a plug in which the element of expansion of the insulating member shall be 20 minimized, thereby avoiding the breaking or cracking of said member while in service. As well understood in the art the insulating member is generally constructed of porcelain or equivalent material which is liable to 25 crack from overheating by reason of its contact with the hot gases in the engine cylinder. In the present embodiment of my invention the size of the insulating member is so proportioned to the heat absorbed thereby 30 as to maintain the temperature of the member below the point at which undue expansion and consequent cracking thereof is likely to occur. The insulating member being thus maintained comparatively cool, it 35 follows that the temperature in the cylinder in the vicinity of the plug will be below the point at which lubricating oil finding its way past the piston to the region of the plug, can take fire, thereby preventing any 40 material accumulations of films of unconsumed carbon (resulting from the incomplete combustion of the oil) on the inner terminal of the insulating member, these 45 films, as well understood in the art, being conductors of electricity and thus tending to short-circuit the sparking terminals of the plug. In many cases however the quantity of oil reaching the region of the plug is 50 so large that the accumulations of the carbon films referred to can not be altogether avoided. A further object of my invention therefore is to construct a spark-plug in which these unavoidable carbon film accumulations shall be so disposed as to make 55 short-circuiting of the sparking terminals

practically impossible. A further object is to reduce the quantity of these accumulations to a minimum so as to minimize the danger of short-circuiting, or eliminating it altogether. The advantages of the invention will be apparent from the following detailed description thereof in connection with the accompanying drawing in which—

Figure 1 represents an elevation of my improved spark-plug; Fig. 2 is a middle longitudinal section of the same; Fig. 3 is a cross-section on the line 3—3 of Fig. 2; and Fig. 4 is an elevation of the same on a reduced scale shown in position on the head of an engine cylinder.

Referring to the drawings, w , w' , represent the wire terminals leading from any available source of electric energy, the wire w being held in position on the spark-plug by the screw-cap 1, the opposite wire w' being herein shown conventionally as grounded through the engine cylinder C. The insulating member of my improved spark-plug consists of a one-piece plug 2 of porcelain or equivalent material, the same being traversed axially by the electrode or electric terminal 3, the outer end of which is screw-threaded to receive the screw-cap 1 by which the wire w is anchored, the wire being clamped between the screw-cap and the nut 5 resting on the washers 6, 6. The medial portion of the plug 2 is received in a metallic casing or socket 7 which is in turn screwed to the engine cylinder C as well understood in the art, the socket being formed with an inner annular shoulder s for the support of a gasket 8 against which the plug is shouldered. The plug 2 is likewise formed with an annular ledge or shoulder s' for the support of a gasket 9 against which is firmly driven the inner end of a clamping ring 10 screwed to the inside of the socket 7, as fully shown in Fig. 2.

The plug 2 projects into the socket 7 a considerable distance beyond the shoulder s , said inwardly projecting portion being hereinafter referred to as the "petticoat", and identified by the reference numeral 2'. The outer walls of the petticoat are spaced from the inner walls of the socket thereby leaving an annular space or clearance a between them (Fig. 2). The petticoat is formed with a bottom dome shaped depression, pocket, or chamber h substantially semi-circular in longitudinal section, com-

munition between the chamber and the annular space a being through the annular basin b formed in the socket 7 immediately beyond the shoulder m engaging the walls 5 of the cylinder C. The inner bounding walls of the basin b project to a point beyond the adjacent end of the petticoat 2' when the plug and socket are properly assembled (the word "plug" wherever used without the 10 qualifying word "spark" meaning always the insulating member 2, and "spark-plug" meaning the device as a whole). In other words the edge e of the inner bounding wall of the basin b is disposed within the 15 pocket or chamber h of the petticoat and in a transverse plane beyond the inner terminal (or free edge) of the petticoat, thereby forming a passageway d (between the petticoat and inner wall of the basin b) through 20 which any gases must first dip downward (or toward the bottom of the basin b) before they find their way into the clearance a . The edge e forms the inner terminal of the axial opening or passage-way O formed 25 in the thread section or coupling nipple n of the socket 7, through which opening the inner portion of the electrode 3 passes and beyond which it projects to a point in proximity to the coöperating electrode 3' carried by the part n . The walls of the passage-way O are transversely ribbed or corrugated, in the present embodiment of my 30 invention assuming the form of annular ledges, ribs, or ridges r disposed preferably 35 at right angles to the axis of the passage-way, and in the path of the gases traversing the passage-way, said ridges being connected by sloping walls t . Any other system of roughening or corrugating the walls 40 of the passage-way O would however fall within the spirit of my invention. The cross-section of the passage-way O is sufficient to prevent accidental sparking between the electrode 3 and the walls of said passage-way. The apex of the dome about 45 the chamber h is provided with a socket u for receiving the collar or enlargement 11 formed on the electrode 3, the bottom of the socket being cone-shaped as shown (Fig. 50 2). Obviously, the collar 11 is drawn into firm engagement with the socket bottom when the screw-cap 1 is driven home in clamping the wire w to the plug. Features shown but not alluded to are well understood in the art and require no description 55 in the present connection.

Should any oil or lubricant during the 60 operation of the engine find its way past the piston to the region of the spark-plug, then necessarily with each explosion more or less of the oil would be forced through the passage-way O and projected against the walls of the domed chamber h of the petticoat 2'. A considerable portion of the oil 65 forced through the passage-way O would

be arrested by the corrugations or ribs r against which it would naturally impinge, so that a much smaller quantity would reach the chamber h than would be the case were the bore of the passage-way smooth. 70 Should the oil arrested by the roughened walls of the passage-way O accumulate thereon to any material degree, it can do no harm, for notwithstanding the fact that such oil (whether carbonized or not) is a 75 good electric conductor, the cross-section of the opening O is such that the space between the oil layer and the electrode 3 will always be too great to permit sparking between them. Let us assume that a certain quantity of oil has been projected against the domed chamber h of the petticoat and that by the heat of combustion of the exploding and burning gases the oil is carbonized leaving a permanent deposit of carbon c on the 80 dome of the petticoat chamber as shown in Fig. 2. Such a deposit can do no harm since even though it should take up the current from the electrode 3 it can not communicate it to the socket 7 so as to short-circuit the spark terminals 3, 3'. The oil in being projected or sprayed against the domed chamber h will in a measure be reflected, these reflected portions being in the 85 main projected "downward" (assuming the engine to be standing vertically) through the passage d into the basin b where, to some extent, the oil will lodge and form a layer of carbon c' which is rendered harmless because too far removed from the layer 90 c to short-circuit the terminals 3, 3'. Finally, let us assume that some of the oil spray reaches the space a and is deposited as a layer c'' on the outer walls of the petticoat 2', and that the layers c and c'' are 95 practically continuous so as to form a virtual extension of the electric conductor 3 with which the layer c is inevitably in electric connection. Under those circumstances the resistance which the current would 100 encounter in traversing the carbon layers c , c'' , would be in excess of the atmospheric resistance of the air gap between the sparking terminals 3, 3', so that short-circuiting 105 of these terminals would be highly improbable. Of course the carbon accumulation on the outer walls of the petticoat represents an extreme case and would result only in instances of excessive leakage of oil past the 110 piston into the region of the spark-plug. 115 But even should such an accumulation (c'') take place, the gap between it and the inner walls of the socket (across the space a) would be practically no less than the gap 120 between the sparking terminals (3, 3'); and when we consider the increased resistance offered to the flow of the current through the carbon layers c , c'' , the short circuiting 125 of the members 3, 3', due to the passage of the current either directly from the layer 130

c'' to the metallic socket 7 (where the layer *c''* touches the socket wall) or by a jump across the clearance *a* (where the layer *c''* is not in contact with the socket wall) is 5 highly improbable. The spark-plug as constructed therefore insures a permanent 10 sparking between the terminals of the electrodes 3, 3', within the chamber of the engine cylinder, even under circumstances where engine trouble (due to oil finding its 15 way past the piston into the region of the spark-plug) can not be avoided. The arrows in Fig. 2 represent the approximate paths taken by the projected particles of oil. The area of the walls of the cup-shaped 20 or dished cavity or chamber *h* should be sufficient to accommodate if possible most of the accumulations that are likely to result under normal working conditions, any 25 excesses being taken care of by the basin *b* and the outer wall of the petticoat 2'. Obviously, the longitudinal section of the chamber or pocket *h* (or by whatever name we choose to call it) need not be as shown, 30 but may be any suitable depression whose surface may serve as a depositing place for the spray of oil projected through the opening *O*. The details here shown may be departed from without in any wise affecting 35 the nature or spirit of my invention. In all instances however, the mass of the plug 2 should be sufficient to absorb the heat to which the same is subjected, and subsequently radiate said heat into space so that 40 cracking or breaking due to overheating may not result. Preferably, though not necessarily, the plug 2 is of one piece. The socket or complementary member 7 which supports the plug may of course be of any 45 suitable or ornamental design or pattern, and may assume a construction to which the term "socket" would no longer be applicable. Such changes however would constitute no departure from my invention. It may be stated in passing that the increased area of 50 contact presented to the gases by the corrugations or roughenings *r* as against a

smooth bore, has the effect of reducing the temperature of said gases, so that the danger of carbonizing of the oil is minimized. 55 The omission of the pocket *h* would not be going outside the spirit of my invention, for it is obvious that the insulating member may terminate in a plane face on which the carbon layer *c* may be deposited, but an 58 arched, domed, or dished formation such as the pocket *h* affords a larger surface for the deposit of the carbon than would a plane or blunt end.

Having described my invention, what I 60 claim is:

A spark-plug comprising an outer socket, an inner insulating plug mounted therein and terminating inside the socket in a petticoat spaced from the walls of the socket, 65 the inner walls of the petticoat being domed to form a pocket, a thread section terminating the socket and provided with an axial passage-way discharging into the petticoat pocket, a basin surrounding the discharge 70 end of the passage-way, the edge of the inner wall of the basin forming the inner end of the passage-way aforesaid and disposed in a transverse plane slightly within the pocket of the petticoat whereby a short passage is formed between the free ends of the 75 petticoat and the inner walls of the basin for establishing communication between the passage-way of the thread section of the socket and the basin aforesaid, the basin 80 communicating with the space between the socket and outer walls of the petticoat, an electrode extending axially through the insulating plug and through the passage-way of the thread section of the socket and 85 spaced from the walls of said passage-way, and a coöperating electrode carried by the socket.

In testimony whereof I affix my signature, in presence of two witnesses.
